UNITED STATES PATENT OFFICE.

FERNANDO J. DIBBLE, OF NEW YORK, N. Y., ASSIGNOR TO THE TELEMETER COMPANY OF NEW YORK.

TELE-THERMOMETER.

SPECIFICATION forming part of Letters Patent No. 379,766, dated March 20, 1888.

Application filed May 12, 1887. Serial No. 237,962. (No model.)

To all whom it may concern:

Be it known that I, FERNANDO J. DIBBLE, a citizen of the United States, residing in New York, in the county and State of New York, 5 have invented certain new and useful Improvements in Telemeters, of which the following is a specification.

The invention relates to certain improvements in the organization of electrical apparatus for indicating at distant points variations in temperature, atmospheric pressure, or other similar changing forces occurring at any particular locality by the movements of any regularly-operated device.

15 The invention relates especially to the class of devices described in the patent of Charles L. Clarke, No. 327,526, dated October 6, 1885. The purpose of the invention is to improve the mechanical construction of the apparatus.

20 The invention will be described in connection with the accompanying drawings, in which—

Figure 1 is a top view of the transmitting apparatus, and Fig. 2 is a transverse section 25 of the same. Fig. 1^a is a detail of a portion of the instrument. Fig. 3 is a bottom view of the instrument. Fig. 4 illustrates a modification in the construction of the thermostat adapted to operate the instrument, and Fig. 30 5 illustrates the general organization of circuits and the application of the receiver to the transmitter.

Referring to the figures, C represents a circuit-closing arm, which may be operated in 35 this instance by the variations in the temperature which affect a thermostatic strip, V. This strip is wound in a spiral and is supported at one end from a rigid support, V², to which it is secured by a clamp and screw, v'. 40 The support V² is tubular in form and extends from a suitable base-plate, v⁵, secured to the frame of the instrument.

Through the tube V² there extends a hollow shaft, V', to which the other end of the thermostatic strip V is fastened by a screw, v², entering a suitable lug upon the tubular shaft. This lug passes through a slot in the tube V². By reason of the tubular construction of the parts V and V² air is allowed to circulate 50 freely in the parts, and thus prevent the thermostat from being affected by the heat con-

ducted thereto through the metal. In some instances it may be desired to incase the entire thermostat, and for this purpose a covering, V³, may be employed. This consists of a 55 thin metal shell clamped at its bottom to a flange upon the tube V².

The end of the shaft V' is solid and of small cross-section, as shown at v³, and passes through a suitable bearing, v⁴, in the end of the tube 60 V². Upon the end of v³ is supported the circuit-closing arm C. This is operated by variations in the temperature acting upon the thermostatic strip V. The end of this arm constitutes a contact-point, c. In alignment 65 with the extension v³ there is mounted an arbor, a. This arbor has its bearings in the two plates a' a², the latter being bound to the plate A. Upon the arbor there is carried a block, a⁴, having upon the opposite sides insulating- 7c plates a⁵ a⁶. Against these plates, and in the same plane with each other, there are secured by insulated screws two arms, C' and C², extending upon the opposite sides of the arm C. These arms carry at their respective extremiti- 75 es contact-points c' c², with which it is designed that the arm C shall close circuits accordingly as it is actuated in one direction or the other. The extremities of the arms C' and C² are bound by a screw, c⁸, which is insulated 80 from one of the arms, and therefore does not electrically connect the two arms.

A conductor, 1, electrically connected by a screw, c³, with the arm C', leads to a contact-point, h⁵, hereinafter to be described, and 85 this is connected by a conductor, 2, through the coils of an electro-magnet, H'. The connections are continued from this coil by a conductor, 3, to a contact-point, y², which is applied to a contact-spring, y⁶, and from this 90 spring by the conductor 4 to an electro-magnet, F', and from this magnet by a conductor, 5, to a line, L', leading to the distant station. The connections are completed at the distant 95 station, in a manner which will presently be described, with one pole of the battery O, the other pole of which is connected either directly or through the earth with the frame-plate A of the instrument, and thus through the metal of the instrument with the arm C. 100 When, therefore, the arm C is carried into contact with the arm C', a circuit will be closed

through the electro-magnet H' , thence through the points y^2 and spring y^6 to the magnet F' , and thence out upon the line L' . The magnets H' and F' will therefore be vitalized. The currents which are required for operating the receiving-instruments are of such strength that it is necessary to protect the contact-points c' and c^2 from the electric discharges which are likely to take place upon the interruption of the circuit. For this reason it is desirable to establish a shunt-circuit around these points whenever they serve to close a circuit. For this purpose the electro-magnet H' and a similar magnet, H^2 , are employed.

15 The point h^5 is connected, as already described, with the conductor 2, and the armature-lever h' of the magnet H' is connected with the base of the instrument, and thus with the battery O . When, therefore, the magnet H' has been vitalized, the connections are completed from the conductor 2, leading from the magnet H' through the points h^5 and lever h' to the battery, thus shunting the circuit across the points c and c' . The magnet F' is provided with an armature, F' , carried upon a lever, F^5 . A pawl, l' , is carried upon the lever F^5 , and this impels a wheel, E' , in a given direction when the magnet F' is vitalized. This wheel E' is mounted in the frame of the instrument, and its arbor carries at its end above the plate A a small pinion, e . This pinion engages the teeth of a segment, e' , secured to the block a^4 . When the wheel is moved by the magnet F' , it carries with it the arms C' and C^2 in the proper direction to move the arm C' away from the arm C , and thus interrupt the connections at that point. For the purpose of preventing the magnet F' from operating before the points are shunted it is preferred 40 to make this magnet more sluggish than the magnet H' . The wheel E' is preferably secured to its support by screws e^2 , passing through corresponding slots, which permit the wheel to be adjusted for fractions of degrees 45 when the instrument is set up.

The arm C^2 is connected by a conductor, 6, with a contact-point, h^6 , applied to the lever h^2 of the magnet H^2 , and also by a conductor, 7, through the coils of the magnet H^2 , thence through a conductor, 8, with a contact-point, y' , applied to a contact-spring, y^5 . This spring is connected by a conductor, 9, with the coils of an electro-magnet, F^2 , corresponding to the magnet F' , thence by a conductor, 10, with a main line, L^2 , leading to the distant station. When the arm C makes contact with the arm C^2 , a circuit is closed through this last-named circuit, actuating the magnets H^2 and F^2 and causing the wheel E' to be driven by a pawl, h^2 , carried upon the lever F^6 of the armature F^4 , applied to the electro-magnet F^2 . This, when actuated, carries the wheel E' in the proper direction for moving the point c^2 away from the point c . A suitable retaining-pawl, E^2 , serves to prevent accidental movement of the wheel E' .

It should be here observed that the con-

struction described relieves the thermostat of all work except the closing of the circuit, which it does directly, and not through the intervention of any pinion and wheel or other mechanism, since the arm C is carried directly upon the thermostat. The contact-arms being supported upon the plate a^4 , which is rigid with the segment e' , are then moved 75 by the operation of the electro-magnets through the wheel E' and pinion e .

For the purpose of conveniently arranging the conductors 1 and 6 and holding them away from each other the former is preferably led 80 through an opening in the plate a^6 , while the conductor 6 is led through an opening in the plate a^5 . The plates are provided with extensions sufficient for the purpose. The line L' leads at the receiving-station through a 85 magnet, M' , provided with an armature, m' , carried upon the lever m^2 , which carries the driving-pawl n' . Likewise an armature, m^3 , a lever, m^4 , and a pawl, n^2 , are applied to an electro-magnet, M^2 , included in the line L^2 . 90 When the electro-magnet M' is vitalized, a wheel, N' , is driven in one direction, and when the electro-magnet M^2 is vitalized it is impelled in the opposite direction. In this manner any suitable indicator carried thereby will serve to 95 indicate the operation of the transmitter or the position of the arm C . A suitable retaining-pawl, N , is applied to the wheel N' for preventing it from being accidentally moved.

The conductors leading from the magnets 100 M' and M^2 are connected with the base-plate of the receiving-instrument, and thus through the conductor 11 with an arm, g^5 , applied to a circuit-interrupting device included in a conductor, 12, leading to the battery O . This interrupting device consists of a magnet, Q , included in the circuit of the line L^3 , presently to be described, and vitalized after the several electro-magnets before referred to have operated. A stationary arm, g^4 , carries a contact-spring, g^2 , upon which there is a contact-point, g^3 . This point is connected with the conductor 12. Against this point there normally rests the lever g^5 . The armature g^4 of the electro-magnet Q is normally held away 115 from its magnet; but when the magnet is vitalized it strikes against one end of the lever g^5 , and thereby carries the contact-point g^3 away from the point g^2 , where it normally rests by reason of the attraction of gravity. The 120 momentum of the lever prevents the point from returning immediately into contact with the point g^2 , and therefore the circuit of the lines L' and L^2 is temporarily interrupted from this point g^3 .

The line L^3 , before referred to, is connected by conductor 13, through the coils of the magnet Q , with a conducting-plate, b . This plate is insulated from the frame and carries two contact-springs, m^7 and m^8 . The levers of the 130 magnets M' and M^2 carry two contact-points, m^5 and m^6 , respectively applied to the springs m^7 and m^8 . These levers are respectively connected with the base-plate of the instrument,

and therefore when either lever is drawn forward it closes the circuit through the corresponding points, m^5 and m^6 , to the line 13, leading through the electro-magnet Q to the line L^3 . This line extends to the transmitting apparatus and is connected with the plate b' , similar to the plate b , which also carries two contact-springs, f^3 and f^4 . The levers F^5 and F^6 carry front contact-points, f' and f^2 , applied, respectively, to the points f^3 and f^4 . When, therefore, either one is in its forward position after having actuated the wheel E, it will close the circuit of the line L^3 to the plate A, with which the levers are respectively connected, thus continuing the connections to the conductor 15, leading from the battery O. In this manner the electro-magnet Q will be vitalized; but it will be seen that before it is vitalized it is necessary for the magnet F' or F^2 and its corresponding magnet, M' or M^2 , to have actuated its lever, thus insuring the operation of the instrument.

The contact-springs y^5 and y^6 have been referred to. These are employed for the following purpose: It may sometimes chance that when the arm C', for instance, is moved away from the arm C the point carried upon the arm C' would strike against the point c on the arm C, and vice versa, unless some means were provided for preventing it. This would be especially liable to occur were the arms adjusted very closely to the points c, and also, if the transmitter should receive a violent blow or jar, the arm C might vibrate so as to make contact with both arms C' and C' at nearly the same instant. To prevent this, the circuit-connections from the conductors 3 and 8 are respectively normally made through the springs y^5 and y^6 and their corresponding points, y' and y^2 ; but when the armature h' is drawn toward its electro-magnet the spring y^5 is allowed to move forward by reason of its own resilience and separate from the point y' . It is adjustable, however, so that it will not separate until just before contact is made with the point h^5 . In this manner the connections of the conductor 8 will be interrupted before the connections of the conductor 2 are completed. The same is true with reference to the spring y^6 and its point y^2 .

The contact-springs h^5 and h^6 , and likewise the springs f^3 and f^4 of the transmitter, and also the springs m^7 and m^8 of the receiver, are preferably supported in metallic posts and are bent or curved around the posts, so as to give sufficient length, and they face outward toward the corresponding contact-point, so that as the levers strike them sliding contacts are formed therewith. In the case of the springs h^5 and h^6 the posts t' , upon which they are carried, are formed with extensions t^2 , which are also secured to the plate A. The post itself is fastened directly against the plate, being insulated therefrom by insulating-washers, and the extension is likewise fastened therein to insure that the posts shall not turn, even if the insulating material should shrink and so

allow the post to become somewhat loosened. The springs y^5 and y^6 are also supported upon posts t^2 , provided with extensions t^4 and insulated in a similar manner. Likewise the posts carrying the adjustable contact-points y' and y^2 are similarly mounted and insulated and prevented from turning.

Suitable non-conducting blocks or pegs, t^5 , are carried upon the armature-levers h' and h^2 for preventing the springs y^5 and y^6 from making metallic contact with the levers, and yet allowing them to move forward when the circuit is to be interrupted in the manner described.

The electro-magnets of the transmitter are preferably supported from the lugs formed on the plate A when the latter is cast, and for the purpose of having the parts held compactly the two magnets F' and F^2 project through corresponding holes made in the plate A. The three lines L' , L^2 , and L^3 preferably lead from the three insulated binding plates or posts t^6 , t^7 , and t^8 , carried upon the insulated block t^9 , secured to the plate A at one side. It has been customary heretofore to employ artificial resistance-shunts around the several electro-magnets for the purpose of reducing the spark occasioned by an interruption of the circuit. In this instance it is preferred to employ small coils r of insulated wire having a high resistance, permanently connected with the respective terminals of the several electro-magnets, and securely fastened to the coils or the coverings of the coils, as shown. This may be accomplished by using a suitable glue or cement. These coils are of fine wire, and, while allowing the passage of the currents of high potential induced in the coils of the magnets upon the interruption of the circuit, very little or practically none of the actuating-currents will traverse them. The advantage of this construction lies in its cheapness and simplicity, and by securing the coils to their respective magnets there is no danger of the small wires being broken during transportation.

In constructing the wheel E' it is preferred to cut narrow slots at the bases of the teeth, as shown at M, for the purpose of preventing the accumulation of dirt in the bottoms of the teeth, which would otherwise interfere with the operation of the instrument.

In Fig. 4 there is illustrated a modification in the construction of the thermostatic device. This consists in securing upon a suitable incasing-plate, A', a short tube, W, into the end of which there is screwed the end of the tube V'. The tube V' extends through the tube V² and the threaded tube W and carries the arm C. The thermostatic strip V is inclosed by a case, V³, fastened at the bottom to the tube V² and surrounding the strip. The tube, however, passes over the outer end of the strip and into the interior, as shown, the interior portion being fastened in any convenient manner to the outer portion. The outer end of the thermostatic strip is fastened to the inner portion of the case V³ by means of the screw

v', while the outer end of the strip carries the tube or rod V'. This form is of service where the apparatus is to be applied to a vat, for instance, and it is desired to place only the 5 thermostatic portion within the vat, as indicated at W'. The tube W screws into a suitable coupling-nut, w², which is preferably insulated in the event that the vat is formed of metal.

10 I claim as my invention—

1. A thermostat consisting of a spiral thermostatic strip, a rigid inclosing-case for the strip, to which one end of the strip is secured, said inclosing-case consisting of an outer shell 15 and a tube integral therewith, extending within the supported end of the strip toward its free end, and closed at the inner end, substantially as described, whereby air or fluid may circulate about and within the spiral.

20 2. In a telemeter, the combination, with a thermostat and a circuit-closing arm moved thereby, of two contact arms upon the respective sides of said circuit-closing arm, a support to which they are rigidly secured, a toothed 25 segment of a wheel carried by said support, a toothed wheel and its arbor, a pinion upon said arbor gearing with said segment, and means for moving the contact-arms through the action of said wheel, substantially as described.

30 3. In a telemeter, the combination of a thermostat, a circuit-closing arm secured to the thermostat, two automatically movable contact-arms applied to the circuit-closing arm upon opposite sides thereof, and a pivoted support to which the contact-arms are rigidly secured.

35 4. In a telemeter, the combination, with a circuit-closing arm, of two contact-arms, a support to which they are secured and from which 40 they are insulated, and a mechanical connection coupling the outer ends of said arms together.

45 5. The combination, in a telemeter, of a circuit-closing arm, a thermostat to which it is rigidly secured, two contact-arms, a segment

of a wheel for moving the contact-arms, and electro-magnets for moving said segment in one direction or the other, accordingly as the circuit is closed through one or the other of the contact-arms.

50 6. In a telemeter, the combination, with actuating electro-magnets and means for closing circuits through the same, of artificial resistances around the coils of the electro-magnets mechanically and rigidly secured to the elec- 55 tro-magnets.

7. In an electrical instrument, a contact-point and a circuit-closing spring therefor formed approximately in the shape of a semi-circle, having an inwardly-projecting extension by means of which it is supported, the supports of said point and spring being movable with reference to each other, substantially as described.

8. In a telemeter, the circuit-closing arm C, 65 the two contact-arms C' and C'', the insulating-plates a⁵ and a⁶, against which they are fastened, the conductor 1, passing through the plate a⁶ and secured to the arm C', and the conductor 6, passing through the plate a⁵ and secured to the arm C'', whereby the wires are held apart, substantially as described.

9. In a telemeter, the combination, with a circuit-closing arm, of a contact-arm, a gear moving therewith, a pinion for operating the same, 75 and an electro-magnet vitalized by the contact of the circuit-closing arm with the contact-arm operating said pinion.

10. In a telemeter, the wheel E', its shaft or arbor, the actuating-magnets for moving the 80 wheel, and the adjustable mounting for the wheel E', consisting of the screws e, entering the shaft and their corresponding slots.

In testimony whereof I have hereunto subscribed my name this 10th day of May, A. D. 85 1887.

FERNANDO J. DIBBLE.
